UNITED STATES PATENT OFFICE

THOMAS H. LEDDEN, OF RIDGWAY, PENNSYLVANIA.

INCINERATOR.

Application filed August 18, 1926. Serial No. 130,004.

This invention relates to incinerators, and the subject matter of the present application is designed as an improvement on the structure shown and described in the patent 5 for an incinerator, issued to me on March 9, 1926, and bearing No. 1,576,289.

The object is to provide an incinerator that may be used with either end uppermost, each end of the improved device being 10 equipped with a grate which may be dumped independently of the other and without the necessity for tilting the main body or casing.

Another object is to provide a reversible 15 incinerator wherein, when the bottom grate is being used to hold material for burning, the upper grate serves to prevent escape of burning embers and the draft may be controlled by means of a lid or closure at the 20 lower end which may be opened to the desired degree for the purpose, or closed and held to cause a slow burning process, the upper end also being equipped with a similar lid or closure which may be fully opened 25 to accelerate the draft or which may be closed to exclude rain, etc.

A final object is to provide a simple, cheaply manufactured and strong and durable device of this character which is supported above the ground to permit the same 30 to be freely rotated to bring either end uppermost to permit all parts to be thoroughly scraped and cleansed, each end having a dumping grate with independent, hinged 35 lids connected thereto, the lids and the grates each having separate means for locking the same closed, and means mounted on said frame for holding the body member in upright position.

40 A full and complete understanding of the invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified, so long as 45 such changes or modifications mark no material departure from the salient features of the invention, as specifically pointed out in the appended claims.

In the drawings, in which similar refer-

ence characters designate corresponding 55 parts throughout the several figures:—

Figure 1 is a perspective view of the improved incinerator.

Figure 2 is a vertical section through the 60 same.

Figure 3 is a horizontal section through the body of the incinerator.

Figure 4 is a detail perspective view of the stand for supporting said body member to permit the same to be rotated. 65

Figure 5 is an enlarged plan view of the two opposite bearings for the body member, the latter being broken away.

Figure 6 is an enlarged detail showing 70 the manner of fastening the grate in position.

The reversible body member 1 is formed of suitable sheet metal formed into a cylinder open at each end and having intermediate spaced ribs 2 for strengthening the 75 structure, and having its end edges formed into marginal beads 3 for the same purpose.

At diametrically opposite points, the body member is provided with outstanding trunnions 4 which are adapted to be removably 80 seated to rotate in seats or bearings 5 secured to the upper ends of inclined legs 6 formed of angle iron and suitably held together at their lower ends by horizontal bars 7 to constitute a strong and durable stand 85 for supporting the body member.

The bearings 5 which are formed of suitable cast metal, are open at their upper ends to permit the trunnions to be easily removed therefrom and said castings are provided 90 with depending legs 8 to which the angle irons 6 are riveted or otherwise secured, and the trunnions are each cast integrally with outstanding arms 9 for connection with the side walls of the body member. 95

One of the trunnions 4, which may be termed the rear trunnion, is provided, where joined to the arms 9, with an integral collar or flange 10 which bears against the inner face of the bearing 5, while the 100 outer end of said trunnion is provided with a terminal flange 11 spaced slightly from the outer face of said bearing to permit a limited amount of lateral play therein, as clearly shown in Figure 5 of the drawings. 105

The opposite, or front trunnion 4 is extended and formed into a crank 4^a to facilitate turning the body member in the bear-

ings and to avoid burning the hands during such operation. The front trunnion is further provided with an enlargement to bear against the inner face of the adjacent bearing 5, said enlargement having a vertically disposed rib 12 to snugly fit between the sides of the bearing, when projected thereinto, to prevent the entire body member from turning in the opposite bearings. The front trunnion also carries a flange or collar 13 spaced somewhat from the outer side of the bearings 5, and having its inner face bevelled or tapered, as shown in Figure 5, for the reception of the slotted or forked portion 14 of a lever which is fulcrumed at its lower end, to the outer face of one of the inclined legs 6, as indicated at 15. The outer face of said forked portion is correspondingly tapered or bevelled to contact with the bevelled inner face of the flange 13, and when said lever is forced towards the trunnion, by means of an upstanding handle 16, the action is to draw the rib 12 into the inner end of the bearing and lock the body member from turning, the said space between the terminal flange 11 and the rear bearing permitting such movement. When the lever handle 16 is rocked outwardly to free such engagement, the said lever is stopped in such movement by a lug 17 formed on the lower end of the lever coming in contact with the adjacent leg 6, as clearly shown in Figure 1.

An annular ring 18 is hingedly connected, as at 19, to each end of the body member, the said hinges 19 being arranged in vertical alinement and permitting the rings to be swung into open position or into closed position with an upstanding flange snugly fitting around the aforesaid terminal beads 3. Each ring 18 is also provided with an outstanding concavo-convex inner portion, the inner margins of which are outwardly pressed to form annular seats 21 around the inner edges of the rings.

Circular grate members 22, formed of heavy wire fabric are placed on the inside of the rings with their margins fitting in the said seats 21 and the same are held thereto by spaced bolts 23, thus readily permitting their removal and replacement when the same become worn or burned out.

The grate members 22 are preferably rounded outwardly into concavo-convex form, as clearly shown in Figure 2 of the drawings, and each ring 20 is provided with a lid or cover 24 hinged thereto, as at 25, and adapted to be closed down over the grates the said lids being similarly formed into concavo-convex shape in accordance with the grates.

The hinges 25 and 19 are all preferably in vertical alinement, and are located on one side of the body member midway between the trunnions 4, so that the lids or

grates or both may be swung downwardly or upwardly without interfering with the legs 6. The lids 24 each have their margins formed into depressions to fit around the seats 21 of the rings, and said lids are held in closed relation to the grates by means of turn buttons 27 mounted in proper positions upon the outer faces of the rings and opposite to the hinges of the same.

The flanges of the rings 18 which extend longitudinally of the body member 1, when the rings are in closed position, are each held in such position by means of a locking lever 28, hinged to the ring, as at 29, and having a slotted intermediate portion to fit over a lug 30 carried by the body member, each hinge element having an outstanding lug 31 to arrest the outward swinging movement of the lever 28 in the unlocking operation and permit same to act as a rigid outstanding handle to force the ring into open position.

With the body member 1 held in upright position and held from turning in the bearings 5 by the lever 14, as shown in Figure 1, the two lids 24 may be opened, as shown, assuming that the material to be burned has been placed in said body member. The full draft upwardly through the incinerator will cause the rapid and complete incineration of said material upon the lower grate, while the upper grate serves to prevent any burning material from flying out of the top. The lower lid 24 may be more or less closed to check the draft or may be locked fully closed to cause slow burning of the contents. The upper lid 24 may also be fully closed to prevent rain from destroying the fire within the incinerator, and it will be readily seen that, after the fire has consumed said material, the ashes may be dumped on the ground by simply releasing the fastening for the lower ring to allow ring and grate to swing downwardly.

What is claimed is:—

1. An incinerator having a cylindrical open-ended body member centrally pivoted at opposite sides to be turned with either end up, closure rings hinged at the ends of the body and adapted to be locked over the same, foraminous grates carried by the rings and adapted to be swung open therewith, and lids separately hinged to the rings and adapted to be locked in covering relation to the grates or to be swung open independently of the same.

2. An incinerator comprising an open-ended cylindrical body, means for supporting said body to permit same to be held with either end on top, a grate located at each end of the body, rings carrying said grates and hinged to the side of the body to swing with said grate to open or closed position, means for locking the rings closed, concavo-convex lids hinged to each ring and

- adapted to be swung independently thereof into open or closed position over the grates, and means for locking said lids in closed position on the rings.
- 5 3. An incinerator including a sheet metal, cylindrical body open at each end, a stand for supporting the body above the ground and permitting same to be inverted to bring either end uppermost, means for locking 10 the body in either position, an annular ring hinged at one side to each end of the body to permit said ring to be swung into closed or open position relative to the end of the body, means for locking the rings closed,
- 15 15 an annular seat formed in the inner edge of each ring, a circular grate marginally held in each seat, a supplemental lid hinged to each ring to be swung open to allow draft through the grate, and means for locking 20 said lid in covering relation to the grate.
4. In an incinerator, an open-ended, cylindrical body member having central, outstanding side trunnions, a stand having bearings in its upper end for said trunnions 25 to hold the body member above the ground, means carried by one of said bearings for

locking the body with either end uppermost, annular rings hinged in longitudinal alignment at one side of the body to be swung shut over the ends of the same, means for 30 locking each ring in closed position, each ring having an upstanding flange around its outer margin to receive the adjacent end of the body member, the inner marginal portion being pressed to form a concavo-convex annulus extending outwardly when the ring is closed, a continuous seat formed by the inner, free edge of the annulus, a circular grate formed of heavy woven wire and fitted and secured in said seat on the 40 inside of the lid, said grate being bent outwardly at its center, a closure lid hinged on the outside of the ring adjacent to the ring hinge, said lid being adapted to be closed and locked over the opening in the 45 ring and being of concavo-convex form to accord with the grate.

In testimony, that I claim the foregoing as my own, I have hereto affixed my signature.

THOMAS H. LEDDEN.
